UNITED STATES PATENT OFFICE

HERBERT C. OTIS, OF SHREVEPORT, LOUISIANA

WELL TUBING SNUBBER

Application filed September 26, 1929. Serial No. 395,314.

This invention relates to snubbing devices, such as are shown and described in my copending application, Serial No. 395,315, filed Sept. 26, 1929, which discloses a method and apparatus for inserting tubing into wells against high pressures existing therein.

The present invention relates to the snubbing devices, one of which is adapted to be moved longitudinally of the tubing in one direction to obtain a grip on the tubing, whereby a movement of the said snubbing device, in an opposite direction, will carry the tubing therewith and force it into the well against the existing pressures therein.

15 The second snubbing device is adapted to grip the tubing and hold the same against movement in a direction out of the well by the pressures existing in the well, while the movable snubbing device is being moved 20 along the tubing to obtain a new purchase thereon.

The construction of the snubbing devices will be fully disclosed hereinafter, reference being had to the accompanying drawings, in 25 which:

Figs. 1 and 2 are respectively a plan view and side elevation of the movable snubbing device;

Figs. 3 and 4 are respectively a plan view 30 and side elevation of the stationary snubbing device;

Fig. 5 is a perspective view of one of the snubbing shoes employed in the snubbing device shown in Figs. 1 to 4 inclusive, and

35 Fig. 6 is a perspective view of one of the snubbing levers which support the said snubbing shoes shown in Fig. 5.

Referring to Figs. 1 and 2, the string of 40 tubing being inserted into the well is indicated at A. This movable snubbing device comprises a carrier 1 composed of a pair of side members 2, 2 located at opposite sides of the tubing A and secured together by means of bolts 3, 3 and spacing sleeves 4, 4 surrounding said bolts respectively.

Pivoted intermediate the side members 2, 2 of the carrier 1 and disposed at opposite sides of the tubing A is a pair of snubbing levers 5, 5, which are respectively 50 mounted on bars 6, 6 extending between and

supported at their opposite ends by the side members 2, 2. The outer ends of the levers 5, 5 are provided with openings 7, 7 respectively for the reception of cables or similar means by which the said levers may be turned on their pivots to effect gripping of the tubing A in the manner disclosed in the said copending application.

The inner end of each of the levers 5 is slotted, as indicated at 8, for the reception 60 of a fin 9 formed on the rear face of a snubbing shoe 10, the said end of the lever 5 and the fin 9 being bored as indicated at 11 and 12 respectively for the reception of a pivot pin 13 by which the shoes 10 are pivotally or 65 loosely mounted on the inner ends of the said levers 5.

The inner faces of the shoes 10, 10 respectively are toothed or serrated as indicated at 14, these faces being concaved and 70 extending substantially around the entire outer surface of the tubing A for the purpose of distributing the pressure exerted by the levers 5 to all points circumferentially of the said tubing to prevent collapsing of the said 75 tubing.

A spring 15 is provided between each of the levers 5 and the shoe 10 carried thereby so that when the pressure is released from the outer ends of the levers 5 the shoes 10 will be drawn to and maintained in a predetermined position relative to the respective levers, whereby the concaved surfaces of the said shoes will be maintained in substantially 80 parallel relationship to the tubing A and providing for self-alignment of the said surfaces of the shoes with the tubing when pressure is applied to the outer ends of the said levers, the upper rear edge of each of the fins 9 being inclined as indicated at 16 for engagement with a similarly inclined surface 17 formed in the base of the slots 8 in the respective levers, when the shoes 10 are not 85 in contact with the tubing.

As indicated in the drawings, the teeth 90 20 formed in the serrated face of each of the shoes 10 are inclined in one direction on one side of each tooth, the other side of the tooth being substantially perpendicular to the plane 95 of the tubing so that when the carrier 1 is 100

moved in one direction along the tubing A the said teeth will glide or ride over the surface of the tubing and when the said carrier is moved in a reverse direction the teeth 20 5 will bite into or firmly grip the surface of the said tubing so that the tubing and the carrier will move concurrently.

The stationary snubbing device illustrated in Figs. 3 and 4 comprises a carrier 1a composed of side frames 2a, 2a secured together at one end by means of bolts 3a and spaced apart by spacing sleeves 4a surrounding the said bolts.

At the opposite end of the carrier the side members 2a, 2a are secured together by bolts 3b and are spaced apart by a block 25 through which the bolts 3b pass.

Intermediate the side frames 2a, 2a is a snubbing lever 5a, pivotally mounted on a pivot bolt 6a, to which is pivoted at 13a a snubbing shoe 10a of the same general character as that above described, a spring 15a being interposed between the lever 5a and shoe 10a for the purposes above noted.

At the opposite side of the string of tubing A is a shoe 30 which is slidably mounted in the carrier 1a between the side members 2a, 2a thereof, the said side frames being provided with slots 31 which are adapted to

receive projections 32, 32 which extend from the opposite sides of the shoe 30 into said slots. The shoe 30, like the shoes 10 and 10a, is provided with a serrated concaved surface 33 which is adapted to engage the outer sur-

face of the tubing A. The opposite end of the shoe 30 is provided with a socket 34 adapted to receive a head 35 formed on one end of a screw-shaft 36 which projects through a threaded aperture formed in the spacing block 25, the opposite end of the screw-shaft 36 being provided with a hand wheel 36a by means of which the shaft 36 may be rotated to effect movement of the shoe 30 in a direction longitudinally of the carrier 1a and laterally with respect to the tubing A. The head 35 of the screw-shaft 36 is held within the socket 34 by means of a plate 37 which is apertured for the passage of the shaft 36 and which is secured to the shoe 30 by means of screws 38, 38.

The carrier 1a is adapted to be secured by bolts 40, 40 to a stationary object such as a fitting B applied to the upper end of the well casing. After the movable carrier 1 has been drawn downwardly toward the stationary carrier 1a thereby forcing the tubing A down into the well casing B against the pressure existing therein the outer end of the lever 5a is forced downwardly by any suitable means such as a cable or a hand bar adapted to be inserted in the openings 7a formed in the said lever for the purpose of moving the shoe 10a into contact with the surface of the tubing which will force the tubing against the serrated surface of the

shoe 30 and between the two the said tubing will be held against movement outwardly with respect to the casing B while the movable carrier 1 is being raised along the tubing A to obtain a new purchase thereon.

The shoe 30 is adapted to be moved laterally of the tubing A for the purpose of permitting the passage of couplings or other devices extending beyond the outer surface of the tubing A as the tubing is being forced down into the well casing.

With the snubbing devices above described, I have been able without loss of gas or oil to insert tubing and to hold the same against pressures which have exceeded 1000 pounds per square inch in the well casings in which the tubing was being inserted which, prior to my invention, was considered impossible or impracticable by those familiar with wells in which such high pressures existed.

By the devices above noted, a considerable saving of gas and oil has been made possible in wells which, prior to my invention, were permitted to flow freely as no means had as yet been perfected which would effect the inserting of tubing into the well by which the gas and oil under such high pressure could be controlled.

I claim:

1. A snubbing device adapted for use in inserting tubing into wells against existing pressures therein, said snubbing device comprising a carrier, a lever pivoted to said carrier, and a shoe loosely mounted on and supported solely by one end of said lever and provided with a rectilinear toothed surface adapted to grip flatly from end to end thereof the surface of the tubing when pressure is applied in one direction to the opposite end of said lever.

2. A snubbing device adapted for use in inserting tubing into wells against existing pressures therein, said snubbing device comprising a carrier, a lever pivoted to said carrier, and a shoe loosely mounted on one end of said lever and provided with a rectilinear toothed surface adapted for self-aligning with and to grip flatly from end to end thereof the surface of the tubing when pressure is applied in one direction to the opposite end of said lever.

3. A snubbing device adapted for use in inserting tubing into wells against existing pressures therein, said snubbing device comprising a carrier, a lever pivoted to said carrier, a shoe loosely mounted on one end of said lever and provided with a rectilinear toothed surface adapted for self-aligning with and to grip flatly from end to end thereof the surface of the tubing when pressure is applied in one direction to the opposite end of said lever, and resilient means for holding said shoe in a predetermined position relative to the lever when the said pressure is released from the lever.

4. A snubbing device adapted for use in inserting tubing into wells against existing pressures therein, said device comprising a carrier, a pair of shoes disposed respectively at opposite sides of the tubing in the said carrier, each shoe having a longitudinally rectilinear transversely curved serrated surface adapted to engage completely from end to end and side to side thereof with the surface of the tubing, and a lever pivoted to said carrier and pivotally connected to one of said shoes for supporting said shoe and for moving said shoe into gripping contact with said tubing.
5. A snubbing device adapted for use in inserting tubing into wells against existing pressures therein, said device comprising a carrier, a pair of shoes disposed respectively at opposite sides of the tubing in the said carrier, each shoe having a serrated surface adapted to engage the surface of the tubing, a lever pivoted to said carrier and pivotally connected to one of said shoes for supporting said shoe and for moving said shoe into gripping contact with said tubing, means for slidably supporting the other of said shoes on said carrier, and means for moving said second shoe laterally with respect to said tubing.
